UNITED STATES PATENT OFFICE.

ANDREW ELY, OF ROCHESTER, NEW YORK, ASSIGNOR, BY MESNE ASSIGNMENTS, TO THERESIA ELY, OF SAME PLACE.

IMPROVEMENT IN SEWER-TRAPS.

Specification forming part of Letters Patent No. **173,925**, dated February 22, 1876; application filed January 24, 1876.

To all whom it may concern:

Be it known that I, ANDREW ELY, of the city of Rochester, in the county of Monroe and State of New York, have invented a certain new and useful Improvement in Sewer-Traps; and I do hereby declare that the following is a full, clear, and exact description of the construction and operation of the same, reference being had to the accompanying drawings, in which—

Figure 1 is a perspective view of the case or shell. Fig. 2 is a similar view of the completed trap. Fig. 3 is a vertical section. Fig. 4 is a top view.

Ordinary sewer-traps have a water-cup at the bottom, into which shuts a valve or trunk to cut off the stench and prevent its upward passage. My improvement differs from these in having a dry chamber at the bottom, with a valve that shuts closely thereto by its own gravity. The filling of dirt into the bottom of this chamber makes the same gas-tight, and when water flows therein the valve opens automatically, allowing it to escape, but always leaving the chamber dry.

The invention consists in a particular construction of the case or shell of the trap, whereby it is adapted to receive the valve, as hereinafter more fully described.

A represents the casing or shell, which is usually made of cast-iron. B is the valve. The upper portion of the case is square in cross-section, as shown at *a*, having a flange at the top which fits the curbing in which the trap is placed. It is covered by the usual grating to prevent the entrance of stones and other obstructions. The back *b* is made inclined from the bottom to about two-thirds the distance up to direct the water forward against the valve. On the front side, about half-way up, is an angular shelf, *c*, extending inward, which leaves a sunken seat, *d*, in which rests the valve. The lower end of the case is on a plane with the vertical front side, which leaves the sunken seat *d* inclined, by which means the valve will shut of its own

weight when there is no pressure on the inside. The valve has journals *f f*, which rest in open hook-bearings *g g* attached on the outside of the case. If desired, the inner edges of the valve, where they strike upon the seat, may be packed with rubber, but this generally is not necessary. The case thus constructed is specially adapted to the fitting of the valve. The inclined back *b* concentrates to a wedge-point at the bottom, by which means the dirt entering settles at the apex and quickly seals the joint at the valve. The inclined shelf *c* projects over the upper edge of the valve, so as to throw off the dirt and prevent it obstructing and sticking the valve, which it would do if the hinge were uncovered. The inclined sunken portion *d* forms a seat for the valve, which is situated at such an angle as to shut by its own weight, but yet open when water gathers upon the inside. The angle of the valve, approximating that of the back of the case, leaves a very thin wedge-space for the dirt to gather in, so that the trap will pack in a very short time after a rain. This angle is such, also, as to insure the ready passage of sticks, &c., which, in going down, necessarily pass endwise, being directed by the incline, and have a ready exit.

I have found, from practical use, that this trap is quite as effective in shutting off stench as a water-trap, while it obviates the great difficulty of freezing, which occurs where water is left standing in the trap.

What I claim as new is—

1. The case A, constructed with the square top *a*, inclined back *b*, angular shelf *c*, and inclined sunken seat *d*, for the fitting of the valve B, as shown and described, and for the purpose specified.

In witness whereof I have hereunto signed my name in the presence of two subscribing witnesses.

ANDREW ELY.
